(57) **CLAIM**

The ornamental design for a stackable, interlocking totem moss pole with stake, as shown and described.

DESCRIPTION

FIG. 1 is a diagram illustrating a front view of an example assembled stake and one pole.

FIG. 2 is a diagram illustrating a perspective view of the example assembled stake and pole of FIG. 1.

FIG. 3 is a diagram illustrating a perspective view of the example assembled stake and pole of FIG. 1, further illustrating an interior for moss.

FIG. 4 is a diagram illustrating a front view of the example assembled stake and pole of FIG. 1, further illustrating the pole connecting to a stake.

FIG. 5 is a diagram illustrating a front view of the example assembled stake and pole of FIG. 1, further illustrating the pole interlocking with a stake.

FIG. 6 is a diagram illustrating a section view of the example assembled stake and pole of FIG. 1, further illustrating a connection.

FIG. 7 is a diagram illustrating a top view of the example assembled stake and pole of FIG. 1, further illustrating a view of an interior area and a drainage feature; and,

FIG. 8 is a diagram illustrating a bottom view of the example assembled stake and pole of FIG. 1, further illustrating a view of an interior area and a drainage feature.
